PREPARATION OF 2-ACYL PYRROLES
FROM 2-ACYLFURANS

Andrew P. Dunlop, Riverside, and Samuel Swadesh, Broadview, Ill., assignors to The Quaker Oats Company, Chicago, Ill., a corporation of New Jersey

No Drawing. Application June 22, 1950,
Serial No. 169,773

12 Claims. (Cl. 260—326.5)

1 This invention relates to the preparation of pyrrole compounds and more particularly to the preparation of 2-acylpyrroles from 2-acylfurans.

We have discovered that by heating a 2-acylfuran with a suitable nitrogen base such as ammonia, a primary aliphatic amine, a mixed aliphatic-aromatic amine or furfurylamine, a 2-acylpyrrole can be obtained. As used herein the term 2-acylpyrrole also includes nitrogen-substituted derivatives of 2-acylpyrroles.

Accordingly, it is an object of the present invention to provide an efficient process for the preparation of 2-acylpyrroles. Another object is to provide a process for the preparation of 2-acylpyrroles in a direct manner which can be easily carried out using relatively inexpensive equipment. A very important object is to provide an improved process for producing 2-acylpyrroles by reacting a 2-acylfuran with a nitrogen base. Other objects and advantages of the present invention will become apparent to those skilled in the art as the invention is more fully described.

Broadly stated, the present invention provides an improved process for the production of 2-acylpyrroles which comprises heating a 2-acylfuran with a suitable nitrogen base at elevated temperatures. In view of the fact that the particular reactants used may be selected from a large list and since the best operating temperature depends largely upon the specific reactants used, the temperature employed may vary from about 50° to 250° C. Generally, we prefer to operate within a temperature range of 80° to 200° C. It is to be understood, however, that higher or lower temperatures may be used with a resultant increase or decrease in the reaction rate in accordance with the general law of chemical reactions.

The proportion of reactants, i. e., 2-acylfuran and the nitrogen base used in our process may be varied over a wide range. Theoretically in our process, one mole of the 2-acylfuran reacts with one mole of the nitrogen base to form a ketimine, or "Schiff's base," and with an additional mole of nitrogen base to form a pyrrole in accordance with the following equations:

2Wherein R may be hydrogen, alkyl, aryl, aralkyl, or a heterocyclic radical. R' may be alkyl, aryl, aralkyl or a heterocyclic radical. R'' may be hydrogen, alkyl, aralkyl or a heterocyclic radical.

The ketimine of the pyrrole is easily hydrolyzed to the 2-acylpyrrole:

Thus, two moles of nitrogen base are required.

20 In practice, however, we prefer to employ an excess of the nitrogen base over the 2-acylfuran.

As a general rule, an added solvent is not necessary in the process, however, under certain conditions a solvent may be desirable. When the employment of a solvent is desirable its selection

25 must be made with care as we have found considerable variance in the ultimate yields of the 2-acylpyrrole with different solvents. For example, when the nitrogen base is ammonia, a competing reaction may occur if ethanol is used

30 as the solvent and a hydroxypyridine may be formed in addition to the 2-acylpyrrole. If a mixed alcohol-water medium, or water alone is used, the competing reaction may proceed to the exclusion of the desired reaction. As another

35 example of the influence of the medium on the reaction, we were not able to detect any pyrrole formation when an ether medium was used under conditions which gave good yields when an alcohol medium or no added solvent was used.

40 In order to disclose the nature of the present invention still more clearly, the following illustrative examples will be given in which "parts by weight" bear the same relation to "parts by volume" as do grams to cubic centimeters.

EXAMPLE 1

Preparation of 2-acetylpyrrole

To 30 parts by weight of 2-acetylpyrrole was added 97 parts by weight of anhydrous ammonia dissolved in 800 parts by volume of ethanol. After heating the solution for about twenty hours at 160 to 165° C. in an autoclave the solution was concentrated to 50 parts by volume by distillation under reduced pressure. The residue, upon cool-

3

ing, yielded 2.9 parts by weight (10 per cent of theory) of crystalline 2-methyl-3-hydroxy-pyridine as a precipitate which had a melting point of 168.3-168.5° C. The filtrate, upon distillation under reduced pressure, yielded 11.1 parts by weight of 2-acetylpyrrole M. P. 90.0-90.5° C. which represented a 38 per cent yield of theory.

Analysis	C	H	N	10
C ₈ H ₇ ON:				
Theory-----	66.1	6.43	12.84	
Found-----	65.84	6.55	12.68	

EXAMPLE 2

Preparation of 2-acetylpyrrole

Thirty parts by weight of 2-acetyl furan was added to 50 parts by volume of liquid ammonia which resulted in a rather vigorous reaction with the formation of acetyl furan ketimine. After the reaction had subsided, 100 parts by volume of liquid ammonia additional was added, the resulting solution heated for 16 hours at 100-110° C. in an autoclave and then the excess ammonia removed by distillation. The residue was dissolved in ether, filtered, ether removed by evaporation and the residue distilled under vacuum. 2.6 parts by weight of 2-acetylpyrrole boiling range 84-87° C. at 2 mm. was obtained which represented a yield of 8.8 per cent of theory.

EXAMPLE 3

Preparation of 1-n-butyl-2-acetylpyrrole

To 30 parts by weight of 2-acetyl furan were added 60 parts by weight of n-butylamine and 350 parts by volume of ethanol. After heating the solution for about 7½ hours at 125-130° C. in the autoclave, the ethanol and excess n-butylamine were removed by distillation and upon further distillation of the residue under reduced pressure 7.8 parts by weight (17 per cent of theory) of 1-n-butyl-2-acetylpyrrole was obtained. The product had a boiling range of 72-74° C. at about 1 mm. Its 2,4-dinitrophenyl-hydrazone derivative melted at 147.0-147.5° C. By further distillation under reduced pressure 9.9 grams of a higher boiling point range (115-135° C. at 1 mm.) was obtained which probably contained the butyl ketimine of 1-n-butyl-2-acetylpyrrole.

Analysis	C	H	N	Mol. wt.
C ₁₀ H ₁₅ ON:				
Theory-----	72.7	9.09	8.48	165
Found-----	72.58	9.37	8.01	163

EXAMPLE 4

Preparation of 1-n-butyl-2-acetylpyrrole

2-Acetyl furan (30 parts by weight) and n-butylamine (60 parts by weight) were autoclaved for 18 hours at a temperature of 150-155° C. cooled and then after removing the excess n-butylamine the product was distilled under a vacuum. A yield of 16.3 parts by weight (36 per cent of theory) of 1-n-butyl-2-acetylpyrrole which had a boiling range of 72° to 74° C. at about 1 mm. was obtained.

EXAMPLE 5

Preparation of 1-n-butyl-2-propionylpyrrole

To 30 parts by weight of 2-propionyl furan was

added 53 parts by weight of n-butylamine and 300 parts by volume of methanol. After heating the foregoing solution for about 17 hours at 160 to 170° C. in an autoclave, the alcohol and excess n-butylamine were removed by distillation under reduced pressure. Upon continuing the distillation of 1 mm., 26.6 parts by weight of distillate was collected and the distillate so collected was refluxed for 15 minutes with 20 parts by volume of 2 normal sulfuric acid. After cooling, the mixture was extracted with ether in 5 increments, the ether layers combined, dried over anhydrous sodium sulfate and the ether removed by distillation. From the extract, 4.4 parts by weight of 1-n-butyl-2-propionylpyrrole having a boiling range of 82° to 84° C. at 1.5 mm. was obtained, equivalent to a yield of 12 per cent of theory.

Analysis	C	H	N
C ₁₁ H ₁₇ ON:			
Theory-----	73.7	9.56	7.82
Found-----	72.51	9.66	7.58

EXAMPLE 6

Preparation of 1-methyl-3,4-dihydropyrrolo [1,2-a] pyrazine

Thirty and 80 parts by weight respectively of 2-acetyl furan and an aqueous solution containing 84 per cent ethylenediamine were heated in an autoclave for about 16 hours at 135° to 150° C. Water and excess ethylenediamine were then removed by distillation under reduced pressure. Upon continuing the distillation at a pressure of 1.8 to 2.5 mm. of mercury, 16.5 parts by weight (equivalent to a 45 per cent yield) of 1-methyl-3,4-dihydropyrrolo [1,2-a] pyrazine having a boiling range of 84° to 89° C. was obtained.

Analysis	C	H	N
C ₈ H ₁₀ N ₂ :			
Theory-----	71.64	7.46	20.90
Found-----	71.60	7.64	21.00

EXAMPLE 7

Preparation of 1-n-dodecyl-2-acetylpyrrole and 1-n-tetradecyl-2-acetylpyrrole

Thirty and 100 parts by weight respectively of 2-acetyl furan and Armeen-12D which is a trade name of a mixture containing 90 per cent dodecylamine, 9 per cent tetradecylamine and one per cent octadecylamine were heated at reflux temperatures for 16 hours in a vessel fitted with a Bidwell trap and then the excess Armeen-12D was removed by distillation. Further distillation at 1 mm. gave a pyrrole rich fraction having a boiling range of 135 to 185° C. Upon careful redistillation of this fraction 12 parts by weight of 1-n-dodecyl-2-acetylpyrrole was obtained boiling at 149° to 159° C. at 1 mm. The 2,4-dinitrophenylhydrazone derivative had a M. P. of 86.0° to 86.5° C. and showed:

Analysis	C	H	N
C ₁₄ H ₂₆ O ₂ N ₂ :			
Theory-----	63.02	7.66	15.32
Found-----	63.11	7.76	15.20

4.2 parts by weight of an additional fraction (1-n-tetradecyl-2-acetylpyrrole) having a boiling range of 168° to 171° C. at 1 mm. was obtained.

Its 2,4-dinitrophenylhydrazone had a M. P. of 79.5° to 80.0° C. and showed:

Analysis	C	H	N
C ₂₆ H ₃₉ O ₄ N ₅ :			
Theory-----	64.32	8.04	14.43
Found-----	63.93	8.17	14.40

EXAMPLE 8

Preparation of 1-n-butyl-5-methyl-2-acetylpyrrole

To 70 parts by weight of 5-methyl-2-acetyl-furan were added 100 parts by weight of n-butylamine and 100 parts by volume of methanol. After heating the foregoing solution for about 21 hours at about 180° C. in an autoclave, the alcohol and excess n-butylamine were removed by distillation under reduced pressure. Upon continuing the distillation at a pressure of about 0.7 mm., 23.7 parts by weight of crude 1-n-butyl-5-methyl-2-acetylpyrrole boiling over a range of 80° to 116° C. was obtained. Redistillation gave 14.2 g. (12% yield) of the pure compound boiling at 94.5° to 95.0° C. at 1.6 mm. A 2,4-dinitrophenylhydrazone derivative melted at 151.8° to 152.6° C. and showed:

Analysis	C	H	N
C ₁₇ H ₂₁ O ₄ N ₅ :			
Theory-----	56.82	5.85	19.50
Found-----	56.60	5.83	19.63

Although the present invention has been described in conjunction with preferred embodiments, it is to be understood that modifications and variations may be resorted to without departing from the spirit and scope of the invention, as those skilled in the art will readily understand. As for example, in addition to the acylfurans enumerated in the specific example, higher members of the homologous series such as butyryl, valeryl, caproyl furans, etc., may be treated with nitrogen bases in a similar manner to produce the corresponding pyrroles. Such variations and modifications are considered to be within the purview and scope of the appended claims.

We claim:

1. A process for the production of a 2-acetylpyrrole which comprises reacting a 2-acylfuran of the general formula:

in which R is an alkyl radical containing not more than 2 carbon atoms with a nitrogen base selected from the class consisting of ammonia and saturated alkyl primary amines at a temperature of 50 to 250° C. wherein the molar ratio of the nitrogen base to the acylfuran is at least 2 to 1.

2. A process for the production of a 2-acetylpyrrole which comprises reacting a 2-acylfuran of the general formula:

in which R is an alkyl radical containing not more than 2 carbon atoms which a nitrogen base

selected from the class consisting of ammonia and saturated alkyl primary amines at a temperature of 80° to 200° C. wherein the molar ratio of the nitrogen base to the acylfuran is at least 2 to 1.

3. A process for the production of a 2-acetylpyrrole which comprises reacting a 2-acylfuran of the general formula:

in which R is an alkyl radical containing not more than 2 carbon atoms with ammonia at a temperature of 50 to 250° C. wherein the molar ratio of the ammonia to the acylfuran is at least 2 to 1.

4. A process for the production of a 2-acetylpyrrole which comprises reacting a 2-acylfuran of the general formula:

in which R is an alkyl radical containing not more than 2 carbon atoms with ammonia at a temperature of 80 to 200° C. wherein the molar ratio of the ammonia to the acylfuran is at least 2 to 1.

5. A process for the production of 2-acetylpyrrole which comprises reacting 2-acetylfuran with ammonia at a temperature of 50 to 250° C. wherein the molar ratio of the ammonia to the acetyl-furan is at least 2 to 1.

6. A process for the production of 2-acetylpyrrole which comprises reacting 2-acetylfuran with ammonia at a temperature of 80 to 200° C. wherein the molar ratio of the ammonia to the acetyl-furan is at least 2 to 1.

7. A process for the production of a 2-acetylpyrrole which comprises reacting 2-acetylfuran with a nitrogen base selected from the class consisting of ammonia and saturated alkyl primary amines at a temperature of 50 to 250° C. wherein the molar ratio of the nitrogen base to the acetyl-furan is at least 2 to 1.

8. A process for the production of a 2-acetylpyrrole which comprises reacting 2-acetylfuran with a nitrogen base selected from the class consisting of ammonia and saturated alkyl primary amines at a temperature of 80 to 200° C. wherein the molar ratio of the nitrogen base to the acetyl-furan is at least 2 to 1.

9. A process for the production of a 1-butyl-2-acetylpyrrole which comprises reacting a 2-acylfuran of the general formula:

in which R is an alkyl radical containing not more than 2 carbon atoms with butylamine at a temperature of 50 to 250° C. wherein the molar ratio of the butylamine to the acylfuran is at least 2 to 1.

10. A process for the production of a 1-butyl-2-acetylpyrrole which comprises reacting a 2-acylfuran of the general formula:

in which R is an alkyl radical containing not more than 2 carbon atoms with butylamine at a tem-

7
perature of 80 to 200° C. wherein the molar ratio of the butylamine to the acylfuran is at least 2 to 1.

11. A process for the production of 1-butyl-2-acetylpyrrole which comprises reacting 2-acetyl-furan with butylamine at a temperature of 50 to 250° C. wherein the molar ratio of the butylamine to the acylfuran is at least 2 to 1.

12. A process for the production of 1-butyl-2-acetylpyrrole which comprises reacting 2-acetyl-furan with butylamine at a temperature of 80 to 200° C. wherein the molar ratio of the butylamine to the acylfuran is at least 2 to 1.
